COIN-CONTROLLED BOTTLE DISPENSING
MACHINE

John B. Brock, Adairsville, Ga., assignor of one-half to William H. Barnhardt, Charlotte, N. C.

Application May 13, 1947, Serial No. 747,632

20 Claims. (Cl. 194—84)

1

This invention relates to a vending machine and more especially to a machine for vending bottles of soft drinks and is preferably coin or check-controlled and comprises in the main a refrigerated compartment having a rack extending from one end of the compartment to the other and provided with spaced upper and lower members and provided with a framework for holding the bottles in spaced relation to each other and preferably in vertical position together with a pair of doors or lids for the two ends of the cabinet and means for locking one door while the other is unlocked so that a customer may deposit a coin and move an operating member which will automatically expose to accessibility one bottle which can be removed from the rack. The customer may raise the lid before or after depositing the coin, but a bottle cannot be removed until a coin is deposited.

The invention comprises a sliding cover which is moved in step-by-step relation and having a biased edge adapted to progressively move in response to a vending operation to fully remove the cover from a bottle to allow it to be removed but preventing the removal of the next bottle until another coin is dropped into the box to thus allow the cover to be moved another step to expose the next bottle. The cover is so designed that when it has been progressively moved from one end of the cabinet to the other to permit all of the bottles to be successively withdrawn from one end of the cabinet, the lid over the empty end of the cabinet will be locked and the lid covering the other end will be unlocked by a single operation and since the cover over the bottles in one end has been completely removed from over the holes in which the bottles were deposited, the cover will then be ready to be moved in a reverse direction in step-by-step relation from over the bottles in the other end of the cabinet and before this operation is carried out, of course, the empty end of the cabinet will be filled with new filled bottles so that they can be refrigerated while the bottles from the other end of the cabinet are being dispensed. This operation of exchanging ends will be carried on progressively as the demand for the soft drinks consumes the bottled drinks from one end or the other of the cabinet.

One of the advantages of the invention is the storage of a great number of bottles in a small amount of space, thus occupying a minimum of floor space. Also, a smaller refrigeration area is provided, which is economical in operation.

Another advantage is that the protecting slideable cover does not have to be re-set when the bottles are exhausted, but only reversed as to di-

2

rection of movement, thus rendering another quantity of refrigerated beverages.

It is thus seen that a single cover will serve for both ends of the cabinet and the same mechanism will move the cover in step-by-step relation relative to a particular end, thus causing one coin-controlled mechanism to control the dispensing of the bottled drinks from either end of the compartment.

10 Some of the objects of the invention having been stated, other objects will appear as the description proceeds when taken in connection with the accompanying drawings, in which

Figure 1 is an isometric view of the cabinet and showing one of the doors slightly raised;

Figure 2 is a top plan view of the cabinet with the center cover section housing the coin-controlled apparatus being removed and both doors being removed;

20 Figure 3 is a vertical sectional view of the upper portion of the cabinet and taken substantially along the line 3—3 and showing parts in elevation and parts broken away;

Figure 4 is an isometric view of the front portion of Figure 3;

25 Figure 5 is a vertical sectional view taken along the line 5—5 in Figure 5;

Figure 6 is a side elevation of the rack or bottle holder which is adapted to fit in the upper portion of the cabinet;

30 Figure 7 is a vertical sectional view of the far side of the rack or bottle holder as seen in Figure 6 and taken along the line 7—7 in Figure 6;

Figure 8 is an enlarged detailed sectional view of the upper left-hand corner of Figure 7;

35 Figure 9 is a vertical sectional view through the cabinet and associated parts and taken substantially along the line 9—9 in Figure 1 and omitting the lower portion of the cabinet;

40 Figure 10 is a top plan view of the front central portion of the center cover portion of the cabinet and taken substantially along the line 10—10 in Figure 3;

Figure 11 is a vertical sectional detail view taken along the line 11—11 in Figure 2;

45 Figure 12 is a vertical sectional view taken substantially along the line 12—12 in Figure 3;

Figure 13 is a vertical sectional view similar to Figure 3 except that the central portion is shown in elevation and the end portions in section and showing the connection between the ends of the center piece and the upper side walls of the cabinet;

50 Figure 14 is a vertical sectional view taken along the line 14—14 in Figure 10.

Referring more specifically to the drawings,

the numeral 20 indicates a cabinet having end walls 21 and 22 and side walls 23 and 24. The cabinet has a bottom 25 secured to the interior surfaces of the end walls and side walls and suitable insulation material 26 is disposed between the outer side walls and outer end walls and a lining member 28 which is preferably metal or other impervious or watertight material so that the cabinet can be used as a wet box or as a dry box as desired.

The lining 28 at its top edges along the sides and ends is bent outwardly as at 30 and has a suitable rubber gasket 31 fixed thereto which fits also into suitable grooves along the upper inner portions of the side walls and end walls.

In the bottom of the compartment formed by the liner 28, suitable refrigeration coils 32 may be disposed which are connected by pipes 33 and 34 to a refrigeration compressor and condenser unit 35 which is driven by a belt 36 which in turn is driven by an electric motor 37.

The two end portions of the cabinet are covered by swinging lids 40 and 41 hinged as at 42 and 43 respectively and each having a handle 44 by means of which the lids 40 and 41 can be raised to gain access to the interior of the cabinet. The front edges of these doors are adapted to be locked in closed position by means to be later described.

Conforming to the interior of the cabinet and extending from side-to-side and end-to-end of the interior of the cabinet is a rack or bottle holder 45 for supporting bottles. This holder comprises four corner posts 50, 51, 52 and 53 and a pair of center posts 55 and 56 disposed on each side of the holder, the upper ends of which are secured to plates 57 which have a plurality of spaced holes 58 in a right-hand plate 57a and a plurality of spaced holes 59 in the left-hand plate 57 as seen in Figure 2, leaving a portion in the middle thereof having no holes therein because this is covered by the coin-controlled mechanism. The holes 58 in plate 57 are made large enough to accommodate soft drink bottles 61. Also secured between the center legs 55 and 56 on each side of the holder is a reinforcing plate 62. The bottom ends of the legs 55 and 56 on each side of the holder are secured together by means of an angle bar 63. Secured below the plate 57 and in spaced relation thereto are plates 64 and 65 which likewise have registering perforations 58a therein in the same manner as plate 57 and through which the bottles 61 pass. This plate 64 is secured at its side and end edges to the upright posts 51, 53, and 55. Plate 65 is secured at its side and end edges by upright posts 56, 50 and 52.

Secured between the corner post 50 and the back post 56 is an angle bar which is identical in all respects and is disposed at the same level as an angle bar 66 secured between the back post 55 and the corner post 51. Between the post 52 and the front center post 56 is secured an angle bar 67 and between the front center post 55 and corner post 53 is secured an angle bar 68. These angle bars have secured to the upper horizontal portions thereof a plurality of cross angle bars 69 which are disposed in spaced relation below the holes 58a in the plate 57 and also below the coinciding holes in plates 64 and 65 so as to centrally engage the bottom of bottles 61 disposed in the rack, thus holding the bottles in an upright position.

Welded on the top outer side edges of the plate 57 are channel bars 75 and 76 which are disposed on one of their sides and have their open sides

facing each other. Slidably mounted on the channel bars 75 and 76 is a cover plate 80 which has its side edges turned downwardly, inwardly and then upwardly as at 81 so that the pointed lower portion of this inturned portion 81 on each side of the cover plate 80 will slide on the lower portion of each of the channel bars 75 and 76. One end of the cover plate 80 is provided with a sloping or biased edge 82 terminating in an arcuate portion 83. The other end of the cover plate 80 likewise has a sloping edge 84 terminating in an arcuate portion 85. The angularity of the edges 82 and 84 is such that as the cover plate is advanced step-by-step it will completely uncover, one at a time, the orifices 58 to allow a bottle therein to be removed but will not sufficiently uncover the next adjacent orifice until the cover plate has been moved another step. The side edges of cover plate 80 are perforated from end to end as at 87 and 88 to form a rack along each edge of the cover plate into which the teeth of suitable pinions, to be presently described, fit for moving the cover plate 80 from one end of the cabinet to the other in step-by-step relation as will be later explained.

Disposed centrally of the channel members 75 and 76 and spanning the distance therebetween is a housing member 90 which has downwardly projecting lips 91 at each end thereof which are secured by riveting or spot welding and the like to the exterior of plates 62 secured between the upper ends of the central legs 55 and 56 on each side of the rack. The member 90 has a bottom 92 extending all the way across the rack and has uprising sides 93 and 94 which are turned inwardly towards each other as at 95 and 96 and have uprising portions 97 and 98. The bottom 92 has two uprising spaced members 100 and 101 in which is rotatably mounted a shaft 102. This shaft near each end thereof has pinions 103 and 104 fixed thereon and the bottom is cut away to form slots 105 and 106 and through these slots 105 and 106 the lower portions of the pinions 103 and 104 project. The teeth of pinions 103 and 104 are adapted to engage the perforations 87 and 88 respectively, whereby the cover plate 80 can be moved towards one end of the cabinet or towards the other depending upon in which direction the mechanism is set to move.

The vertically disposed members 100 and 101 project upwardly into a housing to be presently described. The vertically disposed members 100 and 101 have a plate 107 secured to one edge thereof and which plate has a horizontal portion 108 which projects inwardly and has a perforation therein in which a shaft 109 is rotatably mounted. The plate 108 has a slot 111 through which a coin 112 may drop when a vending operation has been completed. The coin will drop into a coin box 114 to which access may be gained by a suitable door 113 disposed in the upright portion 94.

The lower end of the shaft 109 is mounted in a bearing block 115 disposed on the upper surface of the bottom 92 and this shaft rotatably penetrates the horizontal portion 108 of the plate 107 and has fixedly secured thereon a circular plate 116 having a slot therethrough which the coin 112 may drop and lodge on top of plate 108. The shaft 109 also has loosely mounted thereon a disk 118 which likewise has a slot 119 therethrough through which coin 112 may drop from a coin chute 121 after it is dropped into a slot 122 in a housing 123 of cover member 124. This will

lock disks 116 and 118 together to thus cause shaft 109 to be rotated.

In housing 123 is disposed any suitable slug detecting apparatus for testing the coin before it is allowed to pass into chute 121. In case the coin is rejected, it will be returned to the point 126 on the front of the housing 123.

The disk 116 has integral therewith a pinion 128 which has meshing therewith two racks 129 and 131 which are slidably mounted in the upright members 100 and 101. These racks are spaced apart from each other and mesh with opposed sides of the pinion 128. As they project forwardly, they are bent downwardly and have a horizontal front portion each provided with arcuate slots 132 and 133 respectively. Into these slots 132 and 133 is adapted to fit one at a time a pin 135 mounted in one end of a lever 136 and which has a pin 138 intermediate its ends which projects downwardly through a rectangular hole 165 in a plate 137 and into a slot 139 in a plate 141 which is slidably mounted in suitable slots in the upright portions 93 and 94 of the bridging member 90 and projects substantially from the outer surfaces of the portions 93 and 94. The front end of the link 136 is pivotally secured on a pin 142 which penetrates a slot 144 in cover member 124 and being secured in a slideable handle member 145. The front of the link 136 has a perforation or hole 148 therein which is engaged by one end of a tension spring 149 whose other end is anchored to a spring perch 151 secured on the lower surface of cover member 124. The cover 124 has oscillatably mounted therein a shaft 152 having a handle 153 thereon with a suitable lock 154 therein and the lower end of this shaft 152 has an arm 156 extending laterally therefrom having a downwardly projecting pin 157 which is adapted to slidably fit into a slot comprising two arcuate portions 158 and 159 joined together to make a continuous slot, so formed as to cause pin 157 to move plate 141, when handle 153 is moved.

It is therefore seen that with the parts in the position shown in Figures 2 and 4 that rearward movement of the handle 145 towards the housing 123 will cause rack 129 to be pushed rearwardly which will move shaft 109 in a clockwise direction when viewed looking downward in Figures 2 and 4. This is due to the fact that the pinion 128 which is integral with disk 118 will be moved by the rack 129 and with coin 112 in the position shown in Figure 3, this will cause the disk 116 to be moved which is fixed on the shaft 109.

It is to be noted that the fixed plate 137 has a rectangular opening 165 therein so as to prevent its interfering with movement of pin 138 regardless of the position of the link 136.

The shaft 109 has a worm 166 thereon which meshes with a worm gear 167 fixed on shaft 102 and with the parts in the position shown in Figures 2, 3, and 4, the pinions 103 and 104 will be rotated in a clockwise manner in Figure 4 which will move the cover 80 one step to the left in Figure 2.

It is to be noted by referring to Figure 12 that the upwardly projecting portions 97 and 98 have suitable rubber gaskets 170 and 171 mounted thereon and on which the cover 124 is adapted to rest. This cover 124 is removably fixed in position by means of a projecting member 173 being secured to the lower surface thereof and near the rear end thereof whose free end fits into a suitable opening 174 in the rear side wall of the box. The front end has a suitable lock 175 therein having an arm 176 which is adapted to

move into a slot 177 in the upper edge of the liner 28.

The lids 40 and 41 each have a bracket 180 thereon provided with a slot into which the end of the sliding plate 141 is adapted to engage one at a time to lock either the lid 40 or 41 in closed position when the handle 153 is turned in one of the two directions.

Method of operation

Let us assume that the entire holder 45 is filled with bottles of soft drinks ready to be vended and properly refrigerated. Let us assume that it is desired to first dispense a refrigerated bottled beverage from the right-hand end of the apparatus which will mean that lid 40 will be unlocked and lid 41 will be locked. The owner of the establishment will rotate the handle 153 in a counter-clockwise manner to the position shown in Figure 4. This will move the sliding plate 141 away from the observer in Figure 4. The sliding plate 141 will be thus moved to lock the lid 41 against being raised but will unlock the lid 40 ready for operation. Due to the fact that pin 138 is disposed in slot 139, this will move the link 136 to the position shown in Figure 4 which will move its pin 135 into the slot 133. When a coin is dropped to the position shown in Figure 3 and the customer pushes the handle 145 rearwardly, this will push the rack 129 rearwardly which will impart clockwise rotation to the shaft 109. This will cause the top portion of worm gear 167 to move towards the observer in Figure 4 and thus the pinions 103 and 104 will move the cover 80 to the left in Figure 2 to expose another opening which would be the second from the bottom in the right-hand portion of Figure 1 and its extreme left-hand end portion of the right half of Figure 2. The position of cover 80 in Figure 2 is shown after nearly all of the bottles have been vended from the right-hand end of the cabinet. The bottle would then be accessible to the customer when he lifted the door 40. After the machine will have been operated to successively in step-by-step relation expose the other openings in the extreme left-hand portion of Figure 2 until the last opening has been exposed and the bottle removed, then the proprietor of the establishment in which this apparatus may be located would move the handle 153 a half-revolution in a clockwise manner in Figure 4 which would lock lid 40 and unlock lid 41. However, before this operation, the owner of the establishment would fill the right-hand rack in Figure 2 with a fresh supply of bottled beverages for refrigeration. With the lid 40 locked and the lid 41 unlocked, the apparatus is ready for operation. However, it must be noted that in swinging the sliding plate 141 towards the observer in Figure 4, the pin 138 being mounted in slot 139 would cause the rear end of link 136 to swing towards the observer in Figure 4 and its pin 135 would enter slot 132 in rack 131. Then when a coin is dropped into the apparatus and the handle 145 is moved rearwardly, the rack 131 would be moved rearwardly which would impart counter-clockwise motion to the shaft 109 which would move the top of worm gear 167 away from the observer in Figure 4 which would move the cover 80 one step to the right in Figure 2 to expose the first opening in the first row of the rack at the extreme left-hand end of Figure 2.

It will also be observed that when the handle 145 is moved rearwardly without a coin being 75 in the position shown in Figure 3 that the rack

129 or 131 will not operate shaft 109 for the reason that it requires a coin 112 in the position shown to lock the disk 116 fixed on shaft 109 to the disk 118 which is loosely mounted on shaft 109.

It is also to be observed that the plate 137 has a slot 181 therein and this is for the purpose of allowing the cover 124 to be removed by turning the handle 153 so that it will point back towards the housing 123 and slot 181 will permit the crank 156 to be moved upwardly through this slot.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a machine for vending bottled beverages, a cabinet having two compartments and a lid closing the top of each of the compartments, a bottle holder disposed within each compartment and having a plurality of transverse parallel rows of openings therein for holding a plurality of bottles, a slidable plate disposed above the bottle holders and having its two edges which extend across the compartments biased at a slight angle to the rows of openings, means for imparting a step-by-step movement to the cover plate for moving the biased edge of the plate from obstructing position over one of the openings at a time, the angle of bias of said edges being such as to uncover one opening upon one step of movement of the plate.

2. In a machine for vending bottled beverages, a cabinet having two compartments and a lid closing the top of each of the compartments, a bottle holder disposed within each compartment and having a plurality of transverse parallel rows of openings therein for holding a plurality of bottles, a slidable plate disposed above the bottle holders and having its two edges which extend across the compartments biased at a slight angle to the rows of openings, means for imparting a step-by-step movement to the cover plate for moving the biased edge of the plate from obstructing position over one of the openings at a time, the angle of bias of said edges being such as to uncover one opening upon one step of movement of the plate, and means disposed between the lids and movable relative thereto to unlock one of the lids and to lock the other of the lids so that only bottles from one end of the cabinet at a time can be dispensed.

3. In a machine for vending bottled beverages, a cabinet having two compartments and a lid closing the top of each of the compartments, a bottle holder disposed within each compartment and having a plurality of transverse parallel rows of openings therein for holding a plurality of bottles, a slidable plate disposed above the bottle holders and having its two edges which extend across the compartments biased at a slight angle to the rows of openings, means for imparting a step-by-step movement to the cover plate for moving the plate from obstructing position over one of the openings at a time, the angle of bias of said edges being such as to uncover one opening upon one step of movement of the plate, means disposed between the lids and movable relative thereto to unlock one of the lids and to lock the other of the lids so that only bottles from one end of the cabinet at a time can be dispensed, and means for changing the direction of travel of the slidable plate so that when the bottles in

one end of the cabinet have been dispensed, the bottles from the other end can be dispensed.

4. In a vending machine for vending bottled beverages, a cabinet structure open at the top and having a lid for each end of the cabinet spaced apart from each other, means for refrigerating the interior of the cabinet, a bottle holder disposed within the cabinet and having a plurality of transverse parallel rows of bottle receiving openings, means disposed centrally of the cabinet for locking one lid and unlocking the other lid simultaneously, a cover plate disposed over approximately one-half of the bottle holder at a time, said cover plate having its end portions which extend across the bottle holder disposed at an angle to the transverse rows of bottles disposed in said holder, means for moving the cover plate relative to the holder in step-by-step relation to fully expose one bottle at a time, the angle of bias of the end portions being such as to expose one opening upon each step of movement, coin-controlled means connected to the means for moving the cover plate, and means for changing the direction of movement of the plate so that when all of the bottle receiving openings in one end of the cabinet have been uncovered, the openings in the other end of the cabinet may be uncovered one at a time.

5. In a vending machine having a holder provided with a plurality of aligned rows of package receiving openings, a cover plate disposed over the openings, and having the two end portions which are disposed over the openings disposed at a slight angle to the rows of openings, means for moving the cover plate one step at a time to expose one opening at a time, the angle of bias of said end portions being such as to expose one opening upon each step of movement of the plate, and coin-controlled means for connecting the moving means to the plate to allow the plate to be moved to expose one opening upon the insertion of a coin or check.

6. In a vending machine having a holder provided with a plurality of aligned rows of package receiving openings, a cover plate disposed over the openings, and having the two end portions which are disposed over the openings disposed at an angle to the rows of packages, means for moving the cover plate one step at a time to expose one opening at a time, the angle of bias of said end portions being such as to expose one opening upon each step of movement of the plate, coin-controlled means for connecting the moving means to the plate to allow the plate to be moved to expose one opening upon the insertion of a coin or check, a lid covering each of the two end portions of the rack, means for locking one lid and leaving the other lid in unlocked position, and means for changing the direction of movement of the plate so that when all of the openings in one end of the holder have been uncovered, the openings can be uncovered in the other end of the holder.

7. In a vending machine for vending bottled beverages, a cabinet having an open top and a pair of lids, there being a lid for each end thereof, a housing disposed centrally of the cabinet and covering the central portion of the upper side of the cabinet and against which the proximate edges of the two lids fit, a holder disposed in said cabinet and having a plurality of openings at each end thereof disposed below the lids for containing a plurality of bottles of beverage, said openings being disposed in aligned rows, a cover plate mounted in the cabinet and dis-

posed between the lid and the holder, and having a plurality of perforations along each edge thereof forming a rack, the two edges of the cover plate being biased relative to the rows of openings, a shaft disposed in said housing and having a pair of pinions thereon for engaging the racks disposed along the edges of the cover plate, means for moving the shaft to thereby move the cover plate, the angle of bias of said edges being such as to uncover one opening upon one step of movement of the plate, coin-controlled means for connecting the moving means to the shaft for allowing the cover plate to be moved one step upon the insertion of a coin or check, means for locking one of the lids in closed position and unlocking the other lid so that it can be raised upwardly, and means for reversing the direction of movement of the cover plate so that when all bottled beverages have been exhausted from one end of the cabinet, the lid thereover can be locked and the other lid unlocked and whereby beverages can be delivered from the other end of the cabinet.

8. In a vending machine comprising a refrigerated cabinet, a holder disposed in said cabinet and having a plurality of transversely disposed parallel rows of openings therein for receiving bottled beverages, said holder along its upper side edges having a pair of trackways and a cover plate having its side edges mounted for movement along said trackways, said cover plate having a rack disposed along each edge thereof, the two ends of the cover plate being biased relative to the rows of openings in the rack, means for moving the cover plate relative to the holder in step-by-step movement to completely uncover one opening at a time upon one movement of the plate, the angle of bias of said ends being such as to uncover one opening upon one step of movement of the plate, and means for changing the direction of movement of the cover plate when it has been moved to its limit in one direction to cause a reversal of movement and whereby bottled beverages can be vended from the other end of the holder while additional bottled beverages are being refrigerated in the uncovered portion of the holder.

9. In a vending machine comprising a refrigerated cabinet, a holder disposed in said cabinet and having a plurality of parallel rows of openings therein for receiving bottled beverages, said holder along its upper side edges having a pair of trackways and a cover plate having its side edges mounted for movement along said trackways, said cover plate having a rack disposed along each side thereof, the two ends of the cover plate being biased relative to the rows of openings in the rack, means for moving the cover plate relative to the holder in step-by-step movement to completely uncover one opening at a time upon one movement of the plate, the angle of bias of said ends being such as to uncover one opening upon one step of movement of the plate, and means for changing the direction of movement of the cover plate when it has been moved to its limit in one direction to cause a reversal of movement and whereby bottled beverages can be vended from the other end of the holder while additional bottled beverages are being refrigerated in the uncovered portion of the holder, a centrally disposed housing disposed above the holder and containing the means for moving the rack, a lid hingedly secured to one side of the casing and there being a lid disposed on each side of the casing and covering the top

of the cabinet, and means for locking one of the lids in closed position while leaving the other lid unlocked.

10. In a machine for vending bottled beverages, a cabinet, a bottle holder in said cabinet, the upper end of the cabinet being open, said holder having a plurality of transverse parallel rows of openings therein for receiving bottled beverages, a cover plate slidably mounted in the holder and having its end portions biased relative to the rows of openings in the rack, and means for moving the cover plate in step-by-step relation relative to the rack to completely expose one opening at a time upon each movement of the cover plate, the angle of bias of said ends being such as to uncover one opening upon one step of movement of the plate.

11. In a vending machine comprising a refrigerated cabinet and a bottle holder disposed in the refrigerated cabinet and having a plurality of parallel transverse rows of openings therein for the reception of bottled beverages, a cover plate slidably mounted above the top of the openings and movable in step-by-step relation to the holder, the rows of openings and the edge of the cover plate being biased relative to each other so that upon each movement of the cover plate an opening will become completely unobstructed to permit the withdrawal of a bottle therefrom, each edge of the cover plate having a rack associated therewith and a shaft disposed above the cover plate and having a pinion on each end thereof adapted to engage a rack, and means for moving the shaft to thereby move the cover plate one step to expose an opening in the holder having the openings therein for the reception of bottled beverages.

12. In a vending machine comprising a refrigerated cabinet and a bottle holder disposed in the refrigerated cabinet and having a plurality of transverse parallel rows of openings therein for the reception of bottled beverages, a cover plate slidably mounted above the top of the openings and movable in step-by-step relation to the holder, the rows of openings and the edge of the cover plate being biased relative to each other so that upon each movement of the cover plate an opening will become completely unobstructed to permit the withdrawal of a bottle therefrom, each edge of the cover plate having a rack associated therewith and a shaft disposed above the cover plate and having a pinion on each end thereof adapted to engage a rack, means for moving the shaft to thereby move the cover plate one step to expose an opening in the holder having the openings therein for the reception of bottled beverages, said holder having openings in both end portions thereof and said cover plate being of less length than the combined length of the holder, the other end of the cover plate also having its edge disposed at an angle to the transverse rows of openings in the holder and means for reversing the direction of travel of the cover plate upon its reaching one end of the cabinet to thereby allow the vending of bottles from one end of the holder while the bottles in the other end of the holder are being refrigerated.

13. In apparatus for dispensing bottled beverages comprising an open-topped refrigerated cabinet, a centrally disposed housing extending across the cabinet, a lid disposed on each side of the housing and adapted to expose one end of the housing at a time when a lid is opened, means disposed in the housing for locking one of the

lids and unlocking the other lid in a single operation, a bottle holder disposed within the cabinet and having a plurality of transversely disposed aligned rows of openings for the reception of bottles, a cover plate slidably mounted above the openings and covering a portion of the openings in the bottle holder, one edge of the cover plate being biased relative to the rows of aligned openings, and means for moving the cover plate in step-by-step relation to expose one bottle at a time to permit its removal from the bottle holder, the angle of bias of said edge being such as to uncover one opening upon one step of movement of the plate.

14. A vending machine for bottle beverages comprising a cabinet having a bottle holder disposed therein provided with a plurality of transverse aligned rows of openings for the reception of bottles, a cover plate slidably mounted above the openings and adapted to cover said bottles, the edges of the cover plate being biased relative to the transverse rows of aligned openings, the cover plate having a rack along each edge thereof, a shaft rotatably mounted above the cover plate and having a pinion on each end thereof adapted to mesh with the racks in the cover plate for moving the cover plate, means for imparting rotation to the shaft for a predetermined amount to move the cover plate sufficiently to expose one opening at a time so that a bottle can be removed therefrom, a coin-controlled connection between the shaft and the means for imparting rotation to the shaft for connecting the last-named means to the shaft upon deposit of a coin or check, and means for reversing the movement imparted to the cover plate upon operation of the means for imparting rotation to the shaft so that when the contents of one end of the bottle holder have been exhausted, the other end of the bottle holder can be available for the dispensing of bottles therefrom.

15. In a machine for dispensing bottled beverages, a cabinet open at its top and having a housing disposed intermediate its ends and extending from one side wall of the cabinet to the other, a lid hingedly mounted for vertical movement adjacent each side of the housing, a bottle holder disposed within the housing and having a plurality of openings therein, a sliding cover plate disposed above the openings and having its edges so formed as to expose one opening at a time in the bottle holder when the cover plate is moved, means in the housing for engaging the cover plate for moving it a predetermined amount at each operation, means in the housing for activating the moving means, a coin or check connection between the two means for connecting the same together upon the deposit of a coin or check, means for locking one of the lids and unlocking the other lid simultaneously, and means for reversing the direction of movement imparted to said shaft so that when the bottles have been exhausted from one end of the holder, the bottles in the other end of the holder will be exposed one at a time upon each movement of the cover plate.

16. A vending machine for bottled beverages comprising a cabinet and means for supporting a plurality of bottles in substantially vertical position and arranged in parallel rows, a cover plate movable in a straight line above said rows, the rows and the edge of the cover plate being disposed in an angular relation, and means for moving the cover plate step-by-step a sufficient amount to cause the angular relation between

the parallel rows and the edge of the cover plate to completely uncover one bottle upon each movement of the cover plate.

17. In a vending machine for bottled beverages comprising a cabinet open on its upper side and having a centrally disposed housing bridging the gap between two opposed sides of the cabinet, a lid disposed on each side of the housing for covering the end portions of the top portion of the cabinet, means having rows of openings therein for supporting a plurality of aligned rows of bottles in said cabinet, a slidable cover plate disposed above said openings, the edges of the cover plate and the rows of openings being in angular relation to each other, and means mounted in the housing for imparting step-by-step movement to the cover plate to completely remove the cover plate from over one opening on each step-by-step movement of the cover plate.

18. In a vending machine for bottled beverages comprising a cabinet open on its upper side and having a centrally disposed housing bridging the gap between two opposed sides of the cabinet, a lid disposed on each side of the housing for covering the end portions of the top portion of the cabinet, means having rows of openings therein for supporting a plurality of aligned rows of bottles in said cabinet, a slidable cover plate disposed above said openings, the edges of the cover plate and the rows of openings being in angular relation to each other, means mounted in the housing for imparting step-by-step movement to move the cover plate a sufficient amount to completely remove the cover plate from over one opening on each step-by-step movement of the cover plate, and means for locking one of the lids in position and unlocking the other lid simultaneously.

19. In a vending machine for bottled beverages comprising a cabinet open on its upper side and having a centrally disposed housing bridging the gap between two opposed sides of the cabinet, a lid disposed on each side of the housing for covering the end portions of the top portion of the cabinet, means having rows of openings therein for supporting a plurality of aligned rows of bottles in said cabinet, a slidable cover plate disposed above said openings, the edges of the cover plate and the rows of openings being in angular relation to each other, means mounted in the housing for imparting step-by-step movement to the cover plate a distance sufficient to completely remove the cover plate from over one opening on each step-by-step movement of the cover plate, the means for moving the cover plate comprising a rack associated with each edge of the cover plate and a pair of pinions engaging said rack, said pinions being mounted on a horizontal shaft, a vertically disposed shaft having a driving connection with the horizontal shaft on which the two pinions are mounted, the vertically disposed shaft having a pinion thereon and a pair of racks mounted in said housing and engaging said pinion, and a movable handle member mounted on the housing and being movable to one position to engage one of the racks to move the pinion and the cover plate in one direction, said handle member being movable in another direction to engage the other rack to cause the horizontally disposed shaft to move in the opposite direction to thereby move the cover plate in the opposite direction.

20. In a vending machine for bottled beverages comprising a cabinet open on its upper side and having a centrally disposed housing bridging the

13

gap between two opposed sides of the cabinet, a lid disposed on each side of the housing for covering the end portions of the top portion of the cabinet, means having rows of openings therein for supporting a plurality of aligned rows of bottles in said cabinet, a slideable cover plate disposed above said openings, the edges of the cover plate and the rows of openings being in angular relation to each other, means mounted in the housing for imparting step-by-step movement to the cover plate a sufficient amount to completely remove the cover plate from over one opening on each step-by-step movement of the cover plate, the means for moving the cover plate comprising a rack associated with each side of the cover plate and a pair of pinions engaging said racks, said pinions being mounted on a horizontal shaft, a vertically disposed shaft having a driving connection with the horizontal shaft on which the two pinions are mounted, the vertically disposed shaft having a pinion thereon, and a pair of racks mounted in said housing and engaging said pinion, a movable handle member mounted on the housing and being movable to

14

one position to engage one of the racks to move the pinion and the cover plate in one direction, said handle member being movable in another direction to engage the other rack to cause the horizontally disposed shaft to move in the opposite direction to thereby move the cover plate in the opposite direction, the pinion on the vertically disposed shaft being freely mounted thereon and said vertically disposed shaft having a fixed disk thereon, the pinion on the vertically disposed shaft also having a disk integral therewith and said disks being slotted and whereby a coin may be dropped through a slot in the uppermost disk and lodge in the slot in the lowermost disk to thereby lock the pinion on the vertically disposed shaft to the shaft on which it is mounted to transmit movement of the handle member and a rack controlled thereby to move the transversely disposed shaft and the cover plate in one direction a predetermined distance to expose another opening.
